SHOE WELT UNIT AND METHOD OF MAKING
SAMEHenry B. Gorman, Lynchburg, Va., assignor to
Compo Shoe Machinery Corporation, New York,
N. Y., a corporation of Delaware

Application November 16, 1935, Serial No. 50,070

11 Claims. (Cl. 12—146)

This invention relates to the manufacture of welted shoes, and more particularly to the provision of a welt unit which is especially useful in the manufacture of certain types of such shoes.

In my copending application, Serial No. 38,685, filed August 31, 1935, there is disclosed and claimed a novel method and shoe. In a preferred mode of practicing such method, a welt is attached to a fastening strip to form a welt unit which is attached around the margin of an outsole so that the fastening strip may thereafter be cemented and pressed against the bottom of a lasted shoe upper. The present application is a continuation in part of such copending application, and general objects of the present invention are to provide a welt unit and a method of making the same, such unit being designed and adapted for use in such a shoe.

More particularly, an object of the invention is to provide a preformed welt unit which is adapted to be stitched to an outer sole in position thereafter to be cemented to the bottom of a lasted upper.

Other objects of the invention will in part be obvious and will in part appear hereinafter.

The invention accordingly comprises the several steps and the relation of one or more of such steps with respect to each of the others, and the article possessing the features, properties, and the relation of elements, which are exemplified in the following detailed disclosure, and the scope of the application of which will be indicated in the claims.

For a fuller understanding of the nature and objects of the invention, reference should be had to the following detailed description taken in connection with the accompanying drawing, in which:

Fig. 1 is a fragmentary bottom view of a shoe constructed in accordance with the principles of this invention, most of the outer sole being broken away better to illustrate the interior construction;

Fig. 2 is a transverse vertical sectional view taken through a welt unit used in constructing the present shoe;

Fig. 3 is a transverse vertical sectional view of the welt unit of Fig. 2 showing a further stage in its preparation;

Fig. 4 is a fragmentary longitudinal vertical sectional view taken through the toe portion of an outsole having the welt unit attached thereto;

Fig. 5 is a fragmentary vertical sectional view taken along line 5—5 of Fig. 1;

Fig. 6 is a transverse vertical sectional view

similar to Fig. 2, but showing a modified form of welted; and

Fig. 7 is a transverse vertical sectional view of the welt unit of Fig. 6 showing a further stage in its preparation.

Referring more particularly to the drawing, there is provided a welt strip 10 (Fig. 2) of leather or the like, which may comprise conventional welting of any suitable type heretofore used in the manufacture of men's, women's or children's welt shoes. To this welt strip there is attached a fastening strip 11 by means of stitching 12. The fastening strip is preferably made of a strong, specially woven textile tape or webbing, although any other suitable fabric or light leather may be used if desired. In assembling the fastening strip with the welt, the strip is first doubled as shown in Fig. 2, with its doubled edge overlying the inner edge of the welt strip, with both of its doubled folds extending outwardly above the welt strip. The stitching 12 passes through both folds of the fastening strip near its fold line or crease, and also passes through the welt adjacent its inner edge. This forms a composite welt unit which may be made up in suitable lengths so as to have sections cut off for use in an individual shoe.

The fastening strip 11 is adapted subsequently to be cemented to a lasted upper, and to this end it may, if desired, be impregnated with a suitable adhesive such as pyroxylin or other cellulose derivative cement, latex cement, or the like. It is preferred, however, to apply a coating of such cement to the fastening strip 11 after its attachment to the welt, the strip being undoubled as shown in Fig. 3 to permit the application of cement to both folds thereof. It will be noted that when the strip is thus undoubled by bending back the upper fold thereof and pulling it inwardly, the doubled strip material confined by the stitching 12 in effect forms a small downwardly extending rib or lip 13, to which the welt 10 is sewed and which is located along the inner welt edge. This provides upwardly facing surfaces on the fabric strip on either side of the stitching 12, one cement face comprising the lower fold of the strip and extending outwardly from the stitching or inseam 12, and the other comprising the upper fold of such strip which extends inwardly beyond the inner edge of the welt. The application of cement to the surfaces of the fastening strip at this stage of manufacture is optional, since the adhesive may also be applied later just prior to the attachment of the welt to the upper, or cement may be applied

to the upper and an untreated fastening strip may be pressed thereagainst. When the strip is precoated, or pre-impregnated with pyroxylin cement, this is allowed to dry and is subsequently 5 reactivated by means of a suitable solvent or other cement just prior to the affixing operation which is hereinafter described.

The welt unit is next attached around the marginal edge of a rounded outsole 14, preferably by 10 means of stitching 15, although any suitable cement may be used to join the welt 10 and the outsole 14, if desired. This outsole may be of leather, rubber, composition, or the like. An important feature of the present invention is that 15 these various types of outsoles may be attached to the bottom of a lasted upper by means of cement, which may be relied on to form a firm bond between the fabric strip 11 and the bottom of the shoe. Thus, even inexpensive sole leathers, 20 such as belly leather, can successfully be cement attached to a shoe bottom by means of the present welt unit. Heretofore such leathers could not successfully be utilized in making cemented shoes because their loose, fibrous structure would 25 not withstand the necessary roughing operations used in connection with cementing and still afford a strong cemented bond. It has also been impractical heretofore to attempt to cement rubber and various composition soles directly to the bottom 30 of leather shoes, since a good bond could not be obtained between such materials and the upper leather without resorting to unduly expensive methods.

The welt unit is preferably run entirely around 35 the forward portion of the outsole, and may be extended from the heel breast line on one side of the sole completely therearound to the heel breast line on the other side, the welt butts having the same location that they have in a 40 conventional welt shoe. If desired, the welt may run entirely around the heel portion.

In cases where the welt 10 is of sufficient thickness to make it desirable, filler material 16 is next located on the outsole within the attached 45 welt unit. This filler material preferably is in the form of a dinked out blank of material such as "Onco" or other like fibrous material, and this blank preferably occupies the forepart portion of the outsole extending rearwardly to the ball 50 line.

A lasted upper is provided, preferably comprising an upper 17 having its lasting allowance 18 lasted in flat overlying relation against an insole 19 to which it is affixed by means of pyroxylin cement or the like. McKay stitched or stapled uppers also may be used if desired, and in fact, any form of upper providing a suitable bottom surface for attachment of the fabric fastening strip is contemplated as coming within the pur- 55 view of the present invention. After lasting, the upper is trimmed, roughed and preferably pre-coated with pyroxylin cement in accordance with any suitable or conventional methods heretofore used in the production of cemented shoes. This 60 coating of cement is preferably permitted to dry, subject to later reactivation just prior to the attachment of the fastening strip 11 thereto.

If the thickness of the materials used makes it 65 expedient, further filler material 20 may be packed in the central forepart portion of the lasted upper. It should be understood that the thicknesses of the materials indicated in the present 70 illustrative drawing are considerably exaggerated and that the spaces indicated as being occupied by fillers 16 and 20 in actual practice are not

so large as they appear to be in the drawing, and that where the welt 10 and upper 17 are not unduly thick, very good results can be obtained without using any filler at 16 or 20; or alternatively, one of these fillers may be used and the 5 other dispensed with.

Assuming that a lasted upper has been provided and suitably packed with filler 20, the shoe is now ready for application of the outsole 14. This is done by a simple cement affixing operation wherein the bottom of the upper and/or the fabric fastening strip 11 is coated with adhesive or has its previous adhesive coating activated. The welt equipped outsole is then located with respect to the upper and this assembly is placed 15 in a suitable sole affixing press having a pressure pad or other like means adapted to urge and hold the outsole and its attached fastening strip 11 against the bottom of the lasted upper and this pressure is maintained until the adhesive bond 20 indicated at 21 (Fig. 5) is set. If desired, at any time prior to pressing, the fastening strip can be slashed at the toe or like sharply curved portions better to enable it to lie flatly and snugly 25 against the bottom of the lasted upper.

There is thus provided a shoe wherein the outsole is attached to a welt and the welt is sewed to a lip or rib 13 on the upper, but in which such lip or rib, with its previously associated welt and sole, is easily and effectively applied by a series of 30 relatively simple operations including the described cementing step.

It is also contemplated that the welt unit may be attached to the upper prior to the affixing of the outsole 14 thereto by first cementing or sewing the fastening strip 11 to the bottom of the lasted upper and thereafter sewing or cementing the outsole to the welt. The first described operation is preferred, however, since it provides an easy and effective way of attaching the fastening 40 strip to the bottom of the upper by means of conventional cement sole affixing equipment and does not necessitate a special pressing operation for pre-attaching the welt unit to the upper before the outsole is applied.

In Figs. 6 and 7 a welt unit is shown which is generally similar to that described above, except that the inner edge of the welt 10' is bevelled as at 10''. The fabric fastening strip 11' is doubled along a fold line and this fold line is positioned inwardly over the bevelled surface 10'', both folds of the strip being extended outwardly over the top of the welt. The inseam stitching 12' passes through the inner edge of the welt at or slightly outwardly from the bevelled welt surface, and passes through both folds of the doubled fastening strip somewhat outwardly from its extreme folded edge. When the strip, thus sewed, is undoubled as shown in Fig. 7, it will be seen that the doubled portion confined by the 55 stitching 12' is pulled downwardly in the form of an attaching rib which rests snugly against and is accommodated in the space provided by the bevelled surface 10'', thus avoiding undue downward distortion of the inner edge portion of the 60 welt strip and providing a better fit against the flush surface of the flat outsole to which it is subsequently attached. It will be noted that applicant's combination and relation of the fastening strip with such a bevelled welt (which may be of conventional form) is especially useful for his intended purpose. This welt unit is adapted to be assembled with the outsole and thereafter cemented to the upper in the same manner as the 65 previously described form.

By attaching the outsole in this manner there is provided a construction having marked advantages over previously used welted shoe constructions as to ease and economy of assembly.

- 5 The present shoe also possesses some advantages as compared with conventional cemented shoes in that it is practically impossible to peel the cemented bond between the fastening strip 11 and the bottom of the upper. That is, any kick-
 10 ing or scuffing action which happens to bend down the outsole and welt can only act to separate the welt from the fastening strip 11 back as far as the stitching 12, and any further downward bending force applied to the edge of the
 15 outsole will not have a peeling action tending to separate the strip 11 from the upper. Instead, such force will be applied laterally across the entire cement bond at 21, comprising the folds of the fastening strip which extend both inwardly
 20 and outwardly from the line of stitching where the separating force is applied.

Since certain changes in carrying out the above method, and certain modifications in the article which embody the invention may be made without departing from its scope, it is intended that all matter contained in the above description or shown in the accompanying drawing shall be interpreted as illustrative and not in a limiting sense.

- 30 It is also to be understood that the following claims are intended to cover all of the generic and specific features of the invention herein described, and all statements of the scope of the invention which, as a matter of language, might
 35 be said to fall therebetween.

Having described my invention, what I claim as new and desire to secure by Letters Patent, is:

1. A welt unit adapted for cement attachment to a shoe, comprising a grain leather welt, a
 40 fabric fastening strip sewed to said welt and extending inwardly beyond its inner edge to provide a cementing surface, and a coating of cement on the side of said strip corresponding to the grain side of said welt adapted to engage and
 45 adhere to the bottom of a shoe.

2. A welt unit adapted for cement attachment to a shoe, comprising a leather welt, a fabric fastening strip, stitching joining an intermediate portion of said strip with the inner edge of said
 50 welt, said strip providing cementing surfaces extending inwardly beyond said welt and outwardly beyond said stitching.

3. A welt unit adapted for cement attachment to a shoe, comprising a leather welt, a fabric
 55 fastening strip having a doubled fold therein providing a rib extending downwardly adjacent the inner edge of said welt, stitching joining said welt and rib, one fold of said strip extending outwardly from said stitching and another fold thereof extending inwardly beyond the inner welt edge.

4. A welt unit adapted for cement attachment to a shoe, comprising a welt, a fabric fastening

strip having a doubled fold therein forming a downwardly extending rib adjacent the inner edge of said welt, stitching joining the inner margin of said welt and both folds of said strip, one of said folds being extended inwardly from the inner edge of said welt to provide a cementing surface.

5. A welt unit adapted for cement attachment to a shoe, comprising a welt having a bevelled inner edge, a fabric fastening strip doubled to provide a doubled fold overhanging said bevelled edge, and stitching joining both folds of said strip to said welt along the inner margin of its bevelled portion.

6. A welt unit adapted for cement attachment to a shoe, comprising a welt having a bevelled inner edge, a fabric fastening strip having a doubled fold therein providing a downwardly extending rib occupying the space provided by said bevelled welt edge, and stitching joining the inner margin of said welt and said rib.

7. A welt unit adapted for attachment to a shoe, comprising a welt, a doubled fabric strip extending lengthwise of said welt with its doubled edge adjacent the inner edge of said welt, and stitching connecting said welt and both folds of said strip, one of such folds extending inwardly and the other outwardly from such stitching.

8. A welt unit adapted for attachment to a shoe, comprising a welt, a fabric strip doubled along a fold line, and stitching connecting one edge of said welt with both folds of said strip adjacent said fold line, one of such folds extending inwardly and the other outwardly from such stitching.

9. A welt unit adapted for cement attachment to a shoe, comprising a grain leather welt, a fastening strip extending lengthwise of said welt, a coating of dried pyroxylin cement on said strip, and stitching connecting said welt and strip with the coated surface of the latter facing upwardly in the same direction as the grain side of the welt.

10. A welt unit adapted for cement attachment to a shoe, comprising a grain leather welt, a pyroxylin cement impregnated fabric strip extending lengthwise and inwardly of said welt, and stitching connecting said strip along the inner edge of the grain side of said welt.

11. A method of making a welt unit for cement attachment to a shoe, which comprises, doubling a fabric strip along a fold line, positioning said strip along the upper side of a welt with its folded edge overlying the inner margin of said welt and with its folds extending toward the outer welt edge, stitching the inner welt margin to both folds of said welt close to said fold line, and undoubling the uppermost fold to form a downwardly extending fabric rib adjacent the inner edge of said welt and to provide a cementing surface extending inwardly beyond such edge.

HENRY B. GORMAN.
